F. H. McGURK.

ACETYLENE GAS GENERATOR.
APPLICATION FILED FEB. 5, 1915.

1,165,887.

Patented Dec. 28, 1915.

Fig. 1.

Fig. 2

A cross-sectional view of a circular device. The outermost layer is labeled 12. Inside is a layer labeled 15. A central circular area is labeled 14. Several components are labeled with numbers: 23 is at the top left, 12 is at the top center, 29 is on the left, 28 is on the left side of a central horizontal bar, 28° is on the left side of the bar, 31 is on the left, 30 is at the bottom left, 22 is on the right side of the bar, 10 is on the right, 21 is in the center-right, and 15 is on the right side of the central area. A vertical line labeled 23 extends from the top left to the center.

UNITED STATES PATENT OFFICE.

FELIX H. McGURK, OF PUEBLO, COLORADO.

ACETYLENE-GAS GENERATOR.

1,165,887.

Specification of Letters Patent. Patented Dec. 28, 1915.

Application filed February 5, 1915. Serial No. 6,300.

To all whom it may concern:

Be it known that I, FELIX H. McGURK, a citizen of the United States, residing at Pueblo, in the county of Pueblo and State 5 of Colorado, have invented certain new and useful Improvements in Acetylene-Gas Generators; and I do hereby declare the following to be a full, clear, and exact description of the invention, such as will enable others 10 skilled in the art to which it appertains to make and use the same.

This invention is an acetylene gas generator and relates more particularly to a lamp of that type adapted to be used by miners.

15 An object of the invention is to provide a lamp having multiple carbide reservoirs so arranged that when the carbide in one reservoir has become exhausted, the other reservoir may be employed while renewing the 20 exhausted reservoir, thereby permitting the lamp to be burned continuously.

A further aim of the invention is to reduce to a minimum the danger of explosion of the lamp through overproduction of gas 25 providing for escape of excess gas through the air supply tubes.

30 A further purpose of the invention is to simplify the construction of the device and to provide a lamp which will be of few parts, durable, inexpensive to manufacture, and efficient in operation.

35 Further objects and advantages of the invention will become apparent from the following detailed description taken in connection with the accompanying drawing.

While a preferred embodiment of the invention is illustrated in the drawings, it is to be understood that the disclosure therein made is for the purpose of illustration and 40 not as defining the limits of the invention.

Figure 1 is a rear elevation of the lamp. Fig. 2 is a vertical sectional view through the lamp. Fig. 3 is a transverse section through the water reservoir disclosing the gas and 45 water communications with the carbide reservoir. Fig. 4 is an enlarged detail view of the water tube and control valve.

In the embodiment of the invention herein illustrated, a shell is provided which 50 forms a water reservoir 10. This shell may

be of any preferred material and form, and is shown provided with threaded extensions 11 at the top and bottom thereof. The water reservoir shell, 10, is closed at each end by suitable plates 12, which may be 55 of any appropriate shape to facilitate the flow of water from the water reservoir. The water reservoir chamber may be filled through a port 13, which may be closed by any suitable means. 60

The end walls 12 may be suitably perforated at 14 to permit water to flow from the water reservoir, and may have another perforation through which extends a gas conductor 15. Two of these gas conductors 65 are illustrated, one leading from each end 12 of the water reservoir shell, and extended toward each other where the conductors are bent to extend outwardly, as at 16, beyond the wall of the shell to conduct the gas to a 70 suitable burner tip within a reflector 17.

Communicating with the water aperture 14 of each end wall 12 is a water tube, 18, which is shown provided with an angular member having an aperture 20 adapted to 75 register with the water aperture 14 of the end wall 12. Within this angular section 19 there is positioned a piston 21, which is adapted to be advanced, by a threaded rod 22, to close the aperture 20. This rod 22 is 80 shown extended beyond the wall of the shell and provided with a key 23 to facilitate rotation of the rod 22 to control the supply of water without dismantling the lamp.

The main section 18 of the water tube is 85 adapted to extend into the carbide reservoir, and it is preferred to mount a cleaning wire 24 in this tube 18 to insure the free passage of water through the tube 18, and prevent the tube from becoming clogged 90 with carbide. This wire is preferably threaded at one end 25 to engage threads in the tube 18 for the purpose of retaining the wire in position. At the other end 26, the wire may be provided with a head to facilitate the rotation thereof. If desired, the threaded end 25 may be enlarged to serve as a cleaner member to scrape out the tube 18. This tube 18, may also be provided with a vent aperture 27, intermediate the ends 100

thereof, to permit excess gas to escape through the water tube into the water reservoir chamber.

Within the water reservoir chamber 10 there is positioned an air tube. Two of these air tubes are shown in the drawings, one, 28, having an angular portion 28^a extending through the wall of the shell 10 to communicate with the exterior of the lamp, 19 and having its other end 28^b terminating near the upper end wall 12. The other tube 29 is reversely mounted with its air admission end 29^a positioned at that end of the reservoir shell which is shown as the top 15 in the drawings, and with its other end opening near the bottom end plate 12. These tubes 28, 29 operate alternately to admit air to the water reservoir, and also to serve as means to permit the escape of 20 excess gas from the gas reservoir and from the water reservoir, thereby preventing injury to the lamp.

The carbid reservoirs are in the form of cups 30, which are provided with a threaded 25 contracted end 31 adapted to engage the threaded extensions 11 of the water reservoir shell 10. The carbid reservoirs are interchangeable and are adapted to be used alternately, thereby permitting the removal 30 of one reservoir from the shell to fill the same, while the continued use of the lamp may be effected from the other reservoir.

Each reservoir 30 may be provided with any suitable means to support and retain 35 a fiber or felt filter pad 32, and if desired, its wire mesh support 33.

At the rear of the lamp, there is provided a suitable device to reversibly support the lamp. This means is shown as a double 40 ended hook, the end 34 being shown positioned at right angles to the end 35. The body of the hook is pivotally supported in brackets 35, whereby one end, such as 34 may be used to engage means to support 45 the lamp, while the other end 35 will operate to hold the lamp against movement in one direction on the hook.

In operation, water is placed in the water reservoir 10 through port 18, and is permitted to flow from the water chamber into 50 the carbid reservoir 30 at the bottom of the lamp, through the water tube 18, 21. Gas formed in the carbid reservoir will pass through the filter 32, out through the gas 55 conductor 15 to the burner tip, and should more gas be generated than is consumed, the surplus gas will find its way from the carbid reservoir into the water reservoir through the water tube 18. For this purpose one or 60 more vents 27 may be employed in the tube 18. The gas, on entering the water reservoir, will be conducted to the top thereof and may escape through air tube 28 or 29. When the carbid in the lower reservoir shall 65 have become exhausted, the water valve to

the lower carbid reservoir may be closed by means of the key 23, and the valve to the upper reservoir opened, whereupon the lamp may be reversed to bring the other reservoir into operation, while refilling the exhausted 70 reservoir.

Having thus described my invention, what I claim as new and desire to secure by Letters Patent is:

1. An acetylene gas generator including 75 a water reservoir, a carbid reservoir, and a water tube to connect with said reservoirs, said tube having a water port registering with a port of the water reservoir, a member of the tube being positioned out of alignment with said ports, a threaded seat in said tube member, a core element having an enlarged threaded end to engage said seat when in its inoperative position, the threaded end of said core element operating, when 80 disconnected from its seat and moved longitudinally in the tube member, to free the tube from obstructions.

2. An acetylene gas generator including a water reservoir, a carbid reservoir, and a 90 water tube to connect said reservoirs, said tubes having a water port opening into a water port of the water reservoir, a member of the tube being positioned out of alignment with said ports, and having a threaded 95 seat at one end thereof beyond the water passage, a core element having an enlarged threaded end slightly less in diameter than the internal diameter of said tube and adapted to engage said threaded seat, said 100 threaded end operating to free the tube from obstructions when the core element is moved longitudinally in the tube member.

3. In an invertible acetylene gas generator, a water reservoir having a water port in 10 each end wall, a carbid reservoir removably mounted on each end wall, oppositely directed air conducting means communicating within said water reservoir, oppositely positioned valved angular water tubes serving as means of communication between the water reservoir and the carbid reservoirs, one angular section of the water tubes being mounted on the end wall of the reservoir to register with water ports therein, while 11 the other angular section of the water tubes extends centrally into the carbid reservoirs and near the end wall thereof.

4. In an invertible acetylene gas generator, a water reservoir having a water port 1 in each end wall thereof, a carbid reservoir removably mounted on each end wall, oppositely directed air conducting means mounted within said water reservoir, oppositely positioned valved water tubes serving 1 as means of communication between the water reservoir and the carbid reservoirs, one section of each water tube extending centrally into its respective carbid reservoir, each carbid reservoir having a filter divid-

ing said reservoir into a plurality of chambers, and a safety port in each carbid section of the water tube opening into one of said carbid chambers to permit excess gas to escape from the water tube into the water reservoir and out through the air tubes.

Copies of this patent may be obtained for five cents each, by addressing the "Commissioner of Patents, Washington, D. C."

In testimony whereof, I affix my signature, in presence of two witnesses.

FELIX H. McGURK.
